United States Patent Office.

WILLIAM ROBJOHN, OF NEW YORK, N. Y.

Letters Patent No. 66,395, dated July 2, 1867.

IMPROVEMENT IN LIQUID-METERS.

The Schedule referred to in these Letters Patent and making part of the same.

TO ALL WHOM IT MAY CONCERN:

Be it known that I, WILLIAM ROBJOHN, of the city, county, and State of New York, have invented a certain new and useful Improvement on Water or other Liquid-Meters, of which the following is a full, clear, and exact description, reference being had to the accompanying drawing forming part of this specification, and in which—

Figure 1 represents a front elevation of a meter, constructed according to my improvement.

Figure 2, a partly sectional rear view of the same.

Figure 3, a sectional elevation thereof, parallel and in close proximity to the dial-plate.

Figure 4, a longitudinal view of the prime mover or first driver to the registering motion; and

Figure 5, a transverse section of the valve in connection with its box or case, and passages for changing the direction of the current or flow of liquid through the meter.

Like letters indicate corresponding parts throughout the several figures.

This invention relates to a meter for measuring liquids, capable of being regulated to measure large or small and specified varied quantities; and the nature of the invention consists in certain combinations of mechanism, whereby the meter is made automatically to stop on the required quantity being measured, with instantaneous stoppage of the eduction, and protection against being started without adjustment of the index. Also, in various combinations of mechanism, whereby the general action or working of the meter is improved, and leakage, by dispensing with a stuffing-box to the reciprocating piston of the measuring-cylinder, is avoided.

Referring to the accompanying drawing, A represents the induction pipe of or to the meter, and communicating with a valve-box, B, to which C is the eduction pipe, and D D' the pipes or ways to the upper and lower ends of the working or measuring-cylinder E. The valve F is of the butterfly order, and as it is reciprocated to and fro or oscillated by its shaft a, serves to alternate in a rapid and easy manner the induction and eduction pipes A and C, with the pipes or passages D or D', to reverse the action of the piston G in the cylinder E, and which form of valve is preferable to a four-way cock, having contracted openings through it and controlling said pipes or passages. The piston G has or may have its rod b slotted at or near its top to secure the timely operation, in its reciprocating movement, of a lever, H, that is arranged within a water-tight box or case, I, in communication with the cylinder E at its top, thereby avoiding the necessity of a stuffing-box for or to the piston-rod, and by making the fulcrum-shaft c of the lever H of a conical or taper form, where it fits through the box I, securing, by the pressure of the fluid, a water-tight fit of said shaft. Connected with the shaft c on the outside of the box or case I, is a lever J, to which is pivoted a rod, K, that is in gear through a slot, d, pin e, and regulating-screw f, to adjust the throw, with a lever, L, reciprocated intermittently or at intervals by the connections herein described, at or towards the close of each stroke of the piston G. This lever L is attached to a fulcrum-shaft g, and has jointed to it at its outer end a rod, h, which, by means of a crank or arm, i, connected with the valve-shaft, reverses the position of the valve F to automatically, or by the operation of the piston G, vary the induction and eduction to and from the upper and lower ends of the measuring-cylinder. The gear of the rod h, with the arm i of the valve, is a slotted one, so that it is not till after the lever L has been suddenly shot at or towards the close of the piston's stroke, that the valve F is reversed in a sudden and positive manner as usual, and well understood to be necessary in other water or liquid-meters. This sudden shooting of the lever L is or may be effected as follows: Fast to said lever is a double-inclined bar or plate, M, forming a culminating point at the centre of its one edge. Bearing against this double-inclined bar is a roller, j, carried by an arm, k, furnished with projections or ears l, and pivoted to a lever, N, that is borne or pressed forward by a spring, m, so that in the up or down motion of the lever L, and on the culminating point or centre of the double-inclined bar, passing the axial line of the roller j, which occurs when the piston in the measuring-cylinder arrives at the end of its stroke, the roller, borne forwards by the action of the spring m, presses on the inclined surface or edge of the bar M, to suddenly shoot the lever L, and so reverse the action of the valve E. Connected with the fulcrum-shaft g, of this lever L, is a lever or arm, O, that carries at its outer end a slotted bar, P, having studs n, which gear, in the manner of a mangle-rack, with a double toe, Q, hung on a shaft or spindle, q, in such manner as that, on each throw, up or down, of the bar P, by the operation of the lever L, said toe and its shaft are rotated half a circle, and on the following throw, up or down, of

the arm P, the motion of the shaft and its toe continued the other half of the circle. This serves to operate the first driver of the registering motion or gear, which driver is composed of or by the body of the spindle q, slotted at its centre, and formed into teeth or studs r, on either side, and which gear with a pinion, R, are secured each throw to a perfect lock with said pinion, and the double toe Q adjusted to its proper position by a spring, S. The spindle of the pinion R carries a one-toothed disk, T, which gears once in each revolution with a wheel, U, while the pinion R itself, in addition to gearing with the teeth r of the driver, also gears with a spur-wheel, V. The spindles or shafts of the pinion R, and, wheels U and V, carry the indicating fingers s t u, on the dial, and which system of indicators may be multiplied to any desired extent by the addition of appropriate gear to effect the register, as is well understood by those acquainted with meters generally. The shaft of the wheel V is made capable of a longitudinal sliding movement, so as to lock or be thrown out of gear with the pinion R. Said wheel may be thrown out of gear by means of a spring, v, pressing on the inner end of its shaft, and be held in gear by a pin, w, projecting from the rear face of the dial, and bearing against the outer rim of the wheel V, until, during the rotation of the latter, a hole, x, comes opposite said pin, when the spring v shoots the wheel out of gear, and locks it by the projection of the pin w through it. By this means the meter may be made to pass or measure any or a varied specified quantity, and then to automatically cease, by turning the dial finger connected with the wheel V to a suitable point or figure on the dial, so as to bring the hole x a given distance from the pin w, such distance in the circle or rim of the wheel from the pin w, varying accordingly as it is required to arrest the action of the meter to a small, large, or any intermediate quantity of liquid required to be passed and measured or registered. To effect the arrest of the general as well as the registering action of the meter by the shooting of the wheel V out of gear and into lock with the pin w, the longitudinal movement of the spindle of said wheel is made to control a stop-cock, W, on the education pipe, so that not only is the general action of the meter stopped by arresting the flow, on the wheel V being shot out of gear and locked, but the escape of liquid remaining in the measuring-cylinder arrested. This is accomplished by means of a clutch-lever, y, operated by the longitudinally sliding spindle of the wheel V, and connected with a rock-shaft, X, that carries an arm, z, which, on the wheel V being shot out of gear, acts upon an upper shoulder, a², to a vertical sliding-rod, Y, that, being depressed, operates, by a lower collar, b², to trip a spring-borne catch-lever, c², the inner end of which is thereby released from lock or gear, with a cam-shaped formation to or of a hand-lever, Z, that controls the stop-cock W, and which, on being thus thrown out of lock with the catch-lever c², is shot back by the action of a spring, A², to close the stop-cock, nor can this stop-cock lever Z be again locked with the catch-lever c², and stop-cock kept open, till said catch-lever is again put into locking position by the setting of the wheel V into registering gear, when, on throwing the stop-cock lever into lock with the catch-lever, the meter may again be started and run.

What I claim as my invention, and desire to secure by Letters Patent, is—

1. The combination of the reciprocating piston G, with its rod b, measuring-cylinder E, water-tight box or case I, and lever H, all for operation together and with outside mechanism, substantially as specified.
2. The combination, with the shaft c, of the lever H, of the arm J, slotted bar K, lever L, double-inclined bar or plate M, and roller j, for operation together as herein set forth.
3. The combination of the lever O, slotted bar P, provided with studs r, in mangled rack-gear, with a double toe, Q, and driver q, furnished with teeth r, essentially as and for the purpose specified.
4. The longitudinally sliding spring-borne wheel V, having an aperture, x, in combination with a locking stop, w, and geared with a stop-cock, W, for control of the latter substantially as herein set forth.
5. The rod Y, operated as described, spring-catch c², and stop-cock lever or handle, controlled by a spring, all for operation together, essentially as and for the purpose or purposes specified.

WILLIAM ROEJOHN.
